SEGMENTED TRACK

Robert E. Sausaman, Akron, Ohio, assignor to The B. F. Goodrich Company, New York, N. Y., a corporation of New York

Application November 26, 1954, Serial No. 471,383

10 Claims. (Cl. 305—10)

This invention relates to tracks for track-laying vehicles, and more particularly to tracks for this purpose characterized by an assembly of individual track segments connected end-to-end, and in which each of the track segments includes one or more rubber-covered flexible tension bands to sustain the longitudinal tension in the track.

A segmented track structure has been recently developed embodying a flexible tension band which is reinforced internally with a metal tension member composed of a plurality of flexible reinforcing members such as wire stranded cables and a pair of anchor plates to which the ends of the cables are secured. This metal tension member is embedded in a surrounding body of rubber with the cables disposed lengthwise through the rubber body in a common plane and the anchor plates are disposed transversely to the cables at each end of the band. The terminal ends of the cables at each anchor plate project into openings in the anchor plate and the ends are collectively secured to the plate by swaging or otherwise deforming the anchor plate to constrict the openings into gripping engagement with the cables.

The present invention is directed to an improved mode of swaging the anchor plates to their respective cables which provides a considerably stronger connection between each anchor plate and its respective cables than has been previously obtained. This new mode of swaging provides a connection which is approximately as strong as the tensile strength of the cables. Briefly, this is accomplished by swaging areas or faces of the plate adjacent the openings in which the cable ends are disposed so that the openings are constricted generally radially into gripping engagement with their respective cables and along a substantial length of the ends of the cables. By swaging the faces of the anchor plates in areas intermediate the openings relatively deeply and simultaneously swaging areas of the faces overlying and/or underlying the cables to a lesser depth, the cross-sectional area of each opening is materially reduced so that its respective cable end is squeezed tightly by the constricted portion of the opening.

The invention will be further described with reference to the accompanying drawings, which illustrate a segmented track structure embodying bands of metal tension members made in accordance with this invention.

In the drawings:

Fig. 1 is a plan view showing the sprocket and bogie-engaging side of portions of a segmented track formed with several track segments coupled together, portions of the segments being broken away;

Fig. 2 is a plan view drawn on an enlarged scale showing the manner of coupling an end of a band of one segment to the corresponding band of an adjoining segment, parts of the coupling plates being broken away;

Fig. 3 is a cross-sectional view taken on the lines 3—3 of Fig. 2, and

Fig. 4 is a perspective view of an anchor plate partly

broken away and some cables secured therein in accordance with this invention.

Referring to the drawings, the track structure shown in Fig. 1 is formed by assembling together end-to-end several individual track segments such as track segment A, B and C. The track segments include laterally-spaced, flexible tension bands 10 which extend lengthwise of each segment and the ends of which are coupled to the ends of the corresponding bands of the adjoining segments. The structure of each tension band is of the same general type as described and claimed in the co-pending application Serial No. 386,796 filed October 19, 1953, now Patent No. 2,803,504 of Daniel F. Lynch. Each tension band 10 is formed with a flexible rubber body 14 and has embedded within it a plurality of flexible metal wire stranded cables 16 extending lengthwise of the rubber body from an anchor plate 17 at one end of the band to another similar anchor plate 17 at the opposite end. The anchor plates 17 are disposed transversely to the cables at the ends of the band and each plate is swaged against its respective group of cable ends. The cables and the endwise anchor plates 17 compose an integral element of each band, and this assembly is hereinafter referred to as the "tension member" of each band.

The track segments shown in Fig. 1 further include a plurality of ground-engaging grousers 18 which are fastened transversely across the pair of bands 10 to lugs 19 which project laterally through the sides of the bands from cross-plates 20 which are embedded within the rubber body 14 of the band at equally spaced intervals along the length of the bands to provide a connection between the flexible cables 16 and the grousers. At each grouser, intermediate the bands 10, there are upstanding guide members 21 flanked by driving lugs (not shown).

The guides and lugs are engaged by sprockets (not shown) of the vehicle on which the track is mounted for operation. This general arrangement of the grousers, cross-plates, guides and bands is described and claimed in United States Patent 2,494,066 to C. O. Slemmons.

The anchor plates 17 (see Fig. 4) are each flat bars of malleable metal which are slightly thicker than the diameter of the cables and which are provided with a plurality of laterally-spaced mutually parallel openings 25 extending sideways through the thickness of the plate from its forward edge 26 to its rearward edge 27. The lateral spacing of the openings 25 is equal to the lateral spacing between the cables when they are embedded in the rubber body so that the ends of the cables extend straight into their respective openings 25 of the anchor plates without being kinked or deflected. The mouth of each of the openings 25 at the forward edge 26 of the anchor plate is preferably belled or funnel-shaped so that the cable may be flexed through a substantial angle relative to the anchor plate without being pinched or creased by the mouth of the opening. Each anchor plate is formed with upper and lower flat faces 29 and 30, respectively, and the areas 32 of each of these faces as shown in Fig. 4 is swaged against all of the cable ends assembled in the openings 25 to secure the anchor plate to the cables.

The present invention is directed particularly to the nature of the swaged areas 32 in the upper and the lower face of each anchor plate. This new mode of swaging provides a gripping engagement between the anchor plate and each cable, which is approximately equivalent to the tensile strength of the cable; that is to say, the engagement of the anchor plate with each cable is such that the force required to pull the cable out of the anchor plate is approximately equivalent to the force required to break the cable. It may be noted in Fig. 4 that in the swaged areas 32 the portions 34 of the upper face which directly overlies the openings 25, the por-

tions 35 of the lower face which directly underlies the openings 25, and the portions 36 of both faces which are intermediate the openings 25 are each deformed inwardly from their respective faces along a substantial length of the cable. The portions 36, however, are deformed appreciably deeper than the portions 34 and 35, and these portions extend parallel to the cable ends so that the contour of the swaged area 32 in each of the upper and lower faces of the anchor plates is somewhat sinusoidal. Preferably the portions 36 are deformed inwardly to a depth of about three or four times the depth of the deformation of the portions 34 and 35, the depths being measured from the original plane of the swaged area. By deforming the faces of the anchor plates in this pattern substantially all of the metal of the anchor plate immediately surrounding each opening 25 is molded or displaced generally radially toward the opening and thus radially against the cable to exert substantially equal pressure against all sides of the cable. In this manner the diameter of each opening is materially reduced and is brought into tight gripping engagement with its respective cable. The length of the cable end subjected to the constricting action of the opening is accordingly reduced in diameter because the several strands of wire forming the cable are crowded tightly together. Additional fastening is obtained as the metal forming the walls of each opening is urged or squeezed into the interstices between the cable strands at the outer surface of the cables so that the strands are firmly interlocked with the portions of the metal forming the wall of the opening.

The anchor plates are each preferably of a ductile metal and preferably they are made of steel having physical properties comparable to AISI 1020 steel. The thickness of each anchor plate between faces 29 and 30 is preferably about twice the diameter of the cables and the openings 25 are initially formed equal to the diameter of the cables plus a slight clearance (in the order of from 0.002" to 0.005") to permit manual insertion of the cables into the openings. The length of the cable end about which the opening 25 is constricted (in other words, the width of the swaged area 32 as indicated by dimension X in Fig. 4) is at least twice the diameter of the cable and preferably this length is from three to four times the diameter of the cable.

The cable ends preferably extend completely through the width of each anchor plate (see Fig. 2) and the tips of the cables terminate approximately flush with the rearward edge 27 of the anchor plate. The swaged area 32 in the upper and lower faces of the plate are spaced slightly forwardly from the rearward edge by an area 40. Accordingly, the tip of each cable intermediate the areas 40 retains its original diameter after the swaging operation is completed and thus this tip portion, being larger than the diameter of the constricted portion of opening 25 in the swaged area 32, provides an added gripping engagement between the cable and the anchor plate when the cable is pulled axially of the opening 25.

A particular advantage of this mode of swaging is that the gripping action is effected without bending, flexing or breaking the cable ends or strands of the cable ends which would result in weakening the cable.

After each tension member is formed as an integral unit in the foregoing manner, the rubber body 14 is molded around the cables together with the cross-plates 20 to form a tension band. This band is thereafter assembled with other bands and grousers 18, etc. to form track segments as shown in Fig. 1. Adjoining tension bands of the segments may be coupled together by connecting their corresponding anchor plates 17 as shown in Figs. 2 and 3 by means of upper and lower coupling members 44 and 45, respectively. The anchor plates of adjoining bands are fitted back-to-back with their respective rearward edges 27 abutting above a grouser 18 which

underlies the junction. The rubber body 14 of each band terminates short of the anchor plates 17 in an end wall 46, leaving the upper and lower faces 29 and 30 of the anchor plate exposed to receive the coupling members 44 and 45. These coupling members bridge or straddle the abutting anchor plates and are seated against the upper and lower faces of the anchor plates to enclose them, as shown in Fig. 3. Through each of the corners of coupling members there is a hole 48 which registers with the hole 49 (Fig. 4) through the anchor plates to receive a bolt 50 or other fastener to secure the coupling members tightly to the anchor plate. Each of the upper and lower coupling members have a layer of rubber 51 bonded to them of the same contour as the rubber body 14 of the abutting tension band and which abuts the end wall 46 of the rubber body 14 to provide a continuous rubber surface across the junction of the tension bands.

The tension member provided by this invention may be advantageously manufactured by the method and by the use of apparatus as described and claimed in detail in my copending application Serial No. 471,382, filed November 26, 1954. The method generally involves providing a series of plates each equal to the thickness and length of the anchor plates but having twice the width of the anchor plates. The plates are provided with a series of cable-receiving openings extending the width of the anchor plate from edge-to-edge. A series of cables are threaded through these openings so that the cables are strung continuously from one plate to another. Then the plates are positioned in spaced relation lengthwise along the cables and are swaged to the cables in these positions. Thereafter (or simultaneously with the swaging) the plates are severed along their lengthwise centerline transversely to the cables to sever the cables and divide the originally continuous cables and wide plates into individual tension members each having a group of cables of equal length extending between two anchor plates which are half the size of the original plates.

The tension member provided by this invention is adapted for use in a variety of different track segments from the type of segments shown in Fig. 1, which represent a typical construction. The rubber body 14 may be molded around the cables in different forms, and the grousers, driving lugs, guides, and the arrangement of these parts relative to each other may differ widely depending on the type of service and type of vehicle for which the track is to be used.

Variations of the structure and method described in the foregoing may be made within the scope of the appended claims.

I claim:

1. The method of making a tension member for a track segment which comprises providing an anchor plate having upper and lower plane mutually parallel faces on opposite sides thereof and having a plurality of laterally-spaced openings extending into the plate intermediate said faces, inserting one end of a cable into each said opening, and then deforming areas of said upper and said lower faces overlying and underlying said openings inwardly toward the cables and also deforming areas of said upper and said lower faces intermediate the cables inwardly between the cables an amount appreciably deeper from their respective faces of the plate than the deformation of said overlying and underlying areas whereby each said opening is constricted generally radially into gripping engagement with its respective cable end.
2. The method of claim 1 in which said openings are each constricted generally radially about their respective cables along a length of the cable greater than about twice the diameter of the cable.
3. The method of making a tension member for a track segment which comprises providing a pair

of anchor plates each having a plane face and having a plurality of laterally spaced openings extending into one edge of the plate generally adjacent and parallel to said plane face, assembling a plurality of cables with said anchor plate by inserting one end of each cable into its respective opening of one anchor plate and inserting the opposite end of each cable in a corresponding opening of the other anchor plate, then deforming areas of said plane face of each anchor plate overlying the openings and other areas of said face intermediate adjacent openings to constrict each opening along a substantial length of its respective cable to secure the plate to the cables, and deforming said areas of each plate intermediate adjacent openings appreciably deeper relative to said face than said areas overlying said openings whereby in the deformation the material of the plate is displaced generally radially against each of the cables.

4. A tension member for a track, the tension member comprising an anchor plate having a plurality of laterally-spaced openings therein, and a plurality of cables each having a length at one end thereof disposed within an opening, and said plate having portions directly overlying said openings deformed inwardly toward said cable and having other portions intermediate said openings deformed inwardly a greater amount than the aforesaid portions so that material of the plate is displaced laterally toward the adjacent openings, said deformed portions of the plate being of sufficient extent to embrace a substantial length of each cable end and to constrict each of said openings generally radially against its respective cable.

5. A tension member for a track, the tension member comprising an anchor plate having a plurality of laterally-spaced openings therein, and a plurality of flexible reinforcing members each having a length thereof at one end of the member disposed in an opening, each of said openings having a portion located intermediate the ends of the opening and embracing a substantial length of said end of its respective member disposed therein of smaller cross-sectional area than the remaining portions of said opening, and said portion of smaller cross-section being in radial gripping engagement with said portion of its respective member, restricted areas of the surface of said anchor plate being deformed both inwardly and laterally toward the cables to provide said portions of each opening of smaller cross-sectional area.

6. A tension member in accordance with claim 5 in which said flexible members are wire stranded cables, and in which the length of said portion of opening of smaller cross-sectional area is greater than about twice the diameter of said cable.

7. In a track a tension band comprising a body of rubber material, a single integral anchor plate at each end of the body and a plurality of flexible metal-reinforcing members extending from one of said anchor plates lengthwise through said rubber body to the other anchor plate at the opposite end of the body, each anchor plate having an upper plane face and a lower plane face parallel to said upper face and a plurality of laterally-spaced openings extending into the plate intermediate said faces from one edge of the plate, each said opening having an end of one of said reinforcing members disposed therein, said faces of each plate having areas thereof directly overlying and underlying said openings deformed inwardly toward said members and said faces having other areas thereof intermediate said openings deformed inwardly a substantially greater amount than

the aforesaid deformed areas and also laterally toward adjacent openings, said deformed areas being of sufficient extent to embrace a substantial length of the end of each flexible member and to constrict each said opening generally radially against the member disposed therein.

8. In a track, a tension band comprising a body of rubber material, a single integral anchor plate at each end of the body and a plurality of flexible stranded wire cables extending from one of said anchor plates, lengthwise through said rubber body to the other anchor plate at the opposite end of the body, each anchor plate having an upper face and a lower face and a plurality of laterally-spaced openings extending into the plate intermediate said faces from one edge of the plate, each said opening having an end of a cable disposed therein, said faces of each plate having areas thereof deformed both inwardly and laterally toward the cables to provide in each opening a portion intermediate the ends of the opening embracing a substantial length of said end of its respective cable of smaller cross-sectional area than the remaining portions of said opening, said portions of each said opening exerting generally radially directed gripping pressure on its respective cable end.

9. A metal tension member for sustaining driving loads in a self-laying track, the tension member comprising a pair of anchor plates each having upper and lower faces on opposite sides thereof and each plate having a plurality of parallel spaced openings extending into the plate intermediate said faces from one edge of the plate, and a plurality of flexible wire stranded cables extending between said pair of anchor plates with the ends of each cable disposed within corresponding openings of said anchor plates, and areas of each of said upper and lower faces of each anchor plate embracing a substantial length of the ends of the cables in said openings being deformed both inwardly and laterally so that a portion of each opening is constricted radially against its respective cable end, the portions of said deformed areas intermediate adjacent openings being deformed appreciably deeper relative to the surrounding areas in their respective faces than the portions of said deformed areas overlying and underlying said openings to provide said generally radial constriction of each said opening.

10. The method of making a tension band for a self-laying track, which method comprises providing a solid metal anchor plate having opposing faces and a plurality of laterally spaced openings extending into the plate between said opposing faces from one edge thereof, inserting one end of each of a series of wire stranded cables in said openings, and then swaging said opposing faces of the plates to cause the flow of metal of the anchor plate including the regions thereof between the cables both inwardly and laterally toward said cables thereby radially constricting each said opening against a substantial length of the cable end therein.
